UNITED STATES PATENT OFFICE.

LUIZ RIBEIRO, OF FALL RIVER, MASSACHUSETTS.

LATCH FOR CABINET-CLOSURES.

1,377,437.

Specification of Letters Patent. Patented May 10, 1921.

Application filed July 15, 1920. Serial No. 396,421.

To all whom it may concern:

Be it known that I, LUIZ RIBEIRO, a citizen of Portugal, residing at Fall River, in the county of Bristol and State of Massachusetts, have invented new and useful Improvements in Latches for Cabinet-Closures, of which the following is a specification.

This invention relates to latches for cabinet closures, and particularly to latches for the compartment closures of cabinets provided with doors, drawers and the like, the primary object of the invention being to provide means whereby the compartment closures of a cabinet or receptacle may be latched without the use of keys.

A further object of the invention is to provide latch mechanism which will operate to automatically latch the cabinet closures when the latter are closed and which may be released by simple means to release the closures for opening movement, which means may be of a nature to give, if desired, a certain measure of protection against the opening of the compartment closures by an unauthorized person.

A still further object of the invention is to provide means whereby one or more compartment closures will be automatically opened when released for opening movement.

The invention consists of the features of construction, combination and arrangement of parts, hereinafter fully described and claimed, reference being had to the accompanying drawings, in which:

Figure 1 is a front elevation of a cabinet provided with closures latched and released by means of my improved latching and releasing means.

Fig. 2 is a vertical transverse section through the cabinet, showing the closures locked and also showing certain parts which are mounted upon the front wall of the cabinet.

Fig. 3 is a vertical front-to-rear section through the top of the cabinet showing the upper door latch and contiguous parts of the means for retracting the door latches.

Fig. 4 is a top plan view of parts shown in Fig. 3.

Fig. 5 is a horizontal section on the line 5—5 of Fig. 2.

Fig. 6 is a vertical section on the line 6—6 of Fig. 2.

Fig. 7 is a vertical section showing the means associated with one of the upper

drawers for latching and releasing the other upper drawer.

Fig. 8 is a detached perspective view of parts shown in Fig. 7.

Fig. 9 is a detail section on line 9—9 of Fig. 2.

In the illustrated embodiment of my invention I have shown the same applied to a cabinet 1 having an upper compartment 2 closed by a pair of swinging doors 3 and 4, the free edge of one of the doors being provided with a bead 5 to lap over the free edge of the other door when said doors are closed, whereby through the latching of one door 70 both doors may be held latched. The cabinet is also provided at its base with a single wide lower drawer 6 and a pair of narrower upper drawers 7 and 8, the said drawers 7 and 8 being arranged side by side and in 75 parallel relation to each other.

Latch mechanism is provided for holding the doors 3 and 4 closed, and said latch mechanism comprises keepers 9 at the top and bottom of the door provided with the bead 5, 80 which keepers are adapted to be respectively engaged by vertically sliding latch bolts 10 and 11 movable in guides 12 and 13 secured to the front wall of the cabinet 1. A vertically movable rod or bar 14 is arranged at 85 one side of the cabinet and forms a pivotal connection between an upper latch lever 15 and a lower latch lever 16. The lever 15 is intermediately pivoted, as at 17, to the front wall of the cabinet and is jointed at its inner 90 end, as at 18, to the adjacent end of a co-operating latch lever 19, intermediately fulcrumed at 20 to the front wall of the cabinet, the opposite end of said lever 19 being pivotally connected with the latch bolt 10. The 95 jointed ends of the levers 15 and 19 are adapted to break upward to dispose said levers at an angle to each other and move them out of horizontal alignment, so as to throw the relatively outer ends of said levers 100 downwardly, thus projecting the latch bolt 10 into locking engagement with the upper keeper 9. The lever 16 is a single lever pivotally connected at its outer end to the rod or bar 14, intermediately fulcrumed to 105 the front wall of the cabinet as at 21, and pivotally connected at its inner end with the latch member 11, the arrangement being such that the latch 11 will be projected upward into engagement with its keeper or 110 withdrawn from engagement therewith by upward and downward swinging movements

of the inner end of said lever. A suitable exteriorly projecting handle or operating member 22 is provided for rocking the lever 16, and by manipulating this operating member so as to force the inner end of the lever 16 downwardly the lower bolt or latch 11 will be withdrawn from latching engagement with its keeper, and upward movement will be simultaneously transmitted to the rod 14, which in turn will rock the lever 15, moving the jointed ends of the levers 15 and 19 downwardly and thereby moving the inner end of the lever 19 upwardly to withdraw the upper bolt or latch 10 from engagement with its keeper, leaving the doors 3 and 4 free to be opened. The rod or bar 14 is normally sustained and the parts of the latching mechanism referred to maintained in normal latching position by means of a spring actuated slide 23 mounted in a guideway 24 on the top of the cabinet, said rod or bar being connected at its upper end with the slide by means of a cord or other flexible connection 25 running in contact with a guide pulley 26. The pull of the spring 27 acting on the slide 23 tends to support the rod 14 and oppose and limit its downward movement under the action of a spring 28 connecting the lower end of the rod 14 with the cabinet body, which spring 28 draws the rod 14 downward after latch releasing action to normal position, the spring actuated slide 23 and spring 28 thus balancing the motion of the rod 14 and insuring an easy and sensitive action thereof.

The lower drawer 6 is mounted to slide inwardly and outwardly on rails or supports 29 and between suitable guides 30 and said drawer is adapted, when unlatched, to be moved forwardly to open position by the action of a coiled spring 31 terminally connected with the bottom thereof and with the front wall of the cabinet, said spring being placed under tension for drawer opening action when the drawer is moved to closed position. At each side the drawer 6 is provided with a keeper recess 32 and a stop 33, said keepers being adapted to receive sliding latch bolts 34 and 35, movable in suitable guides, to latch the drawer in closed position, the stops 33 being adapted to engage the retracted latches 34 and 35 to limit the opening movement of the drawer. Arranged horizontally and transversely of the cabinet is an actuating bar 36 held in normal position by a retracting spring 37 and movable longitudinally toward the right hand side of the cabinet by means of a suitable exteriorly projecting handle or operating element 38 against the resistance of said spring. Pivottally connected at its upper end with one end of said bar 36 is a lever 39 intermediately fulcrumed to the cabinet body, as at 40, for rocking movement in a direction transversely of the body and pivot-

ally connected at its lower end with the latch bolt 34. Pivottally attached to the opposite end of the bar 36, at its upper end, as indicated at 41, is a lever 42 intermediately fulcrumed upon the cabinet, as indicated at 43. The lower end of this lever 42 is jointed, as at 44, to the upper end of a coöperating lever 45 fulcrumed upon the cabinet at an intermediate point, as indicated at 46, said lever 45 being fulcrumed at its lower end to the sliding latch bolt 35. The two levers 42 and 45 are mounted to swing on their fulcrums transversely of the cabinet body and are normally arranged at an angle with their jointed ends projecting outwardly and said levers out of alignment with each other. When the bar 36 is moved from its normal position toward the right hand side of the cabinet, the upper ends of the levers 39 and 42 will be swung outwardly or in the same direction as the bar, while the lower ends of said levers will be swung in the reverse direction or outwardly. By this means the lever 39 will be actuated to withdraw the latch bolt 34 directly from its keeper 32, while the lever 42 will be actuated to move the upper end of the lever 45 inwardly and the lower end of said lever 45 outwardly, thus withdrawing the latch bolt 35 from engagement with its keeper. The drawer 6 will thereupon be free for opening movement under the action of the spring 31, such movement being limited by the stops 33. When the operating device 38 is released after actuation of the lever 36 in the manner described, a spring 37 will return the bar 36 and latch actuating levers back to normal position. The latches 34 are provided with beveled ends so that when the drawer is moved inwardly such beveled ends will allow the latches to be retracted sufficiently to ride in contact with wear strips 46 upon the sides of the drawer until said latches come into register with the keepers 32, whereupon the latches will snap into engagement with said keepers and lock the drawer in closed position.

The drawers 7 and 8 are mounted to slide on suitable guides 47 and a spring or springs 48, connecting each drawer with the cabinet body, is or are provided for moving the drawer automatically to open position when the drawer is unlatched. Each upper drawer is provided on its underside with a keeper 49, a stop 50, and a wear strip 51 similar to the corresponding parts on the drawer 6, the keepers on the respective drawers 7 and 8 being respectively adapted for coöperation with vertically movable latch bolts 52 and 53. The latch bolt 52 is pivotally coupled to a horizontally extending lever 54 intermediately fulcrumed upon the casing, as at 55, and pivotally coupled at its opposite end by means of a link 56 to one end of an actuating lever 57 intermediately fulcrumed upon the cabinet, as indicated at 58, the other end of the lever 57 being pivotally connected at 59 to the upper end of the lever 54. The lever 54 is normally held in a position to move the latch bolt 52 into engagement with its keeper 49 by means of a spring 60, the lower end of which is pivotally connected to the lower end of the lever 54. The lever 57 is normally held in a position to move the lever 54 outwardly by means of a spring 61, the lower end of which is pivotally connected to the upper end of the lever 57. The lever 54 is normally held in a position to move the latch bolt 52 into engagement with its keeper 49 by means of a spring 60, the lower end of which is pivotally connected to the lower end of the lever 54. The lever 57 is normally held in a position to move the lever 54 outwardly by means of a spring 61, the lower end of which is pivotally connected to the upper end of the lever 57.

ately fulcrumed on the cabinet body, as at 58, and having at its opposite end an exteriorly projecting handle or finger piece 59 whereby it may be manipulated. A 5 spring 60 connects the latch carrying end of the lever 54 with one of the guides and holds such end of the lever normally elevated to maintain the latch bolt 52 in latching position. Upon depressing the operating 10 element 59 the link 56 will be drawn upward to tilt the latch carrying end of the lever 54 downward against the resistance of the spring 60, thus retracting the latch bolt 52 and releasing the drawer 7 for opening 15 movement. The latch bolt 53 is pivotally connected with one end of an actuating lever 61 fulcrumed intermediately upon the cabinet body, as at 62, the latch carrying end of said lever 61 being normally held elevated by a latch projecting spring 63. 20 The opposite end of said lever 61 is pivotally coupled to the forward end of a trip lever 64 intermediately fulcrumed upon the cabinet as at 65 and jointed at its opposite 25 end, as at 66, to the forward end of a second trip lever 67 intermediately fulcrumed upon the cabinet body, as at 68. The rear end of the lever 67 is normally arranged to rest upon the laterally projecting finger 69 30 of the upbent spring arm 70 of a latch trip spring 71 having its other arm 72 suitably secured to a portion of the cabinet. The arm 70 of the spring 71 is disposed in the path of sliding movement of the part 67, 35 so that when said part is moved inwardly and held in latched position the spring arm 70 will be depressed by the weight thereof. When the spring arm 70 is depressed the levers 64 and 67 are arranged in substantially 40 longitudinal alinement, in which position they are maintained by the action of the spring 63, which under such conditions maintains the latch 53 in latching engagement to hold the drawer 8 from opening 45 movement. When however the latch 52 is retracted and the drawer 7 moves to open position and out of engagement and in advance of the spring arm 70, said arm 70 is free for actuating movement and swings 50 the rear end of the lever 67 upwardly. The spring 70 is of a strength sufficient, when released, to overcome the resistance of the spring 63, and as a result of such movement of the lever 67 under pressure of the 55 spring arm 70 depresses the jointed ends 66 of the levers 64 and 67 so as to throw said levers out of longitudinal alinement. This action raises the forward end of the lever 64 and the adjacent end of the lever 61 and 60 depresses the latch carrying end of the lever 61, thus throwing the latch bolt 53 downwardly and releasing it from engagement with said keeper, whereupon the drawer 8 will be freed automatically for opening 65 movement by this opening spring. The latch bolts 52 and 53 have beveled ends to ride in contact with the wear strips 51 to adapt them to be moved backwardly on the closing movement of the drawers 7 and 8 until they come into alinement with the 70 keepers 49, whereupon they will snap into said keepers and latch the drawer in closed position. It will thus be understood that upon the closing of the drawer 7 said drawer will be latched by its latch bolt 52 75 and the drawer will come into engagement with the trip spring 70 and set the trip mechanism of the latch bolt 53 to adapt said latch bolt for latching engagement with the drawer 8 when the latter is closed, in 80 which operation the actuating lever 57 will be returned to normal position.

It will be evident from the foregoing description that my invention provides a cabinet structure having a plurality of closures 85 adapted to be latched without the use of a key and to be opened in a ready and convenient manner, the construction also being such that an automatic opening movement of certain closure members is obtained 90 upon the release of the same for opening movement. Obviously the operating elements of the latching devices may be so arranged or concealed that they may be manipulated only by a person familiar with 95 their location and method of operation, so that if desired a cabinet may be provided with closures which when latched will be proof against opening movement by any but an authorized person or one familiar 100 with the latch mechanism.

Having thus fully described my invention, I claim:

1. The combination with a cabinet having a closure, of means for automatically 105 opening the closure when released for opening movement, two independently pivoted jointed levers, a latch connected with one of the levers for latching the closure in closed position, and actuating means connected 110 with the other lever.
2. In a cabinet closure, a pair of latch bolts, a single lever connected with one of the latch bolts, a pair of independently pivoted jointed levers connected with the other 115 latch bolt, and a common means for operating said single lever and said pair of levers simultaneously.
3. In a latch for cabinet closures, a pair of latching bolts, a single lever connected 120 with one bolt, a pair of independently pivoted jointed levers connected with the other bolt, actuating means for the levers including connecting means between said levers for simultaneously operating the same, and 125 means for yieldingly opposing resistance of the levers and operating means and returning the same after actuation to normal position.
4. In a cabinet closure, a closure member 130

having keepers, sliding latches to engage said keepers, a single lever connected with one of the latches, a pair of independently pivoted jointed levers connected with the other latch, a connection between the levers for simultaneously operating the same, and means for transmitting operating motion thereto.

5. In a latch for cabinet closures, a pair 10 of latch bolts, a single lever for actuating one bolt, a pair of independently pivoted jointed levers for actuating the other bolt, and a longitudinally movable operating element pivotally coupled to the single lever and to one of the pair of jointed levers.

15. In a cabinet closure, a pair of latch bolts, a single lever for actuating one bolt, a pair of independently pivoted jointed levers for actuating the other bolt, a longi-

tudinally movable operating element pivotally coupled to the single lever and to one of the jointed levers, and means acting on said operating element for yieldingly resisting operating movement thereof and returning the parts after actuation to normal position.

20. A cabinet having a pair of sliding drawers, a latch bolt for latching and releasing one of the drawers, a second latch bolt for latching and releasing the other drawer, means for manually operating the first named latch bolt, and means controlled by the first-named drawer for maintaining the second latch bolt in normal latching position and releasing and retracting the same 30 when said first-named drawer is opened.

35. In testimony whero I affix my signature.
LUIZ RIBEIRO.
